Primary Examiner — Joseph Kukella*Assistant Examiner* — Darryl J Dardenne(74) *Attorney, Agent, or Firm* — Addison D. Ault; IPGentleman Intellectual Property Services, LLC(57) **CLAIM**

The ornamental design for a tea infuser, as shown and described.

DESCRIPTION

FIG. 1. is a perspective view of a tea infuser showing the design;

FIG. 2. is a second perspective view thereof;

FIG. 3. is a front elevation view thereof;

FIG. 4. is a rear elevation view thereof;

FIG. 5. is a left side elevation view thereof;

FIG. 6. is a right side elevation view thereof;

FIG. 7. is a top plan view thereof;

FIG. 8. is a bottom plan view thereof; and,

FIG. 9. is a view of the tea infuser showing an open lid. Dotted lines show structural features of the tea infuser, and do not represent elements of the claimed design.
